UNITED STATES PATENT OFFICE.

HENRY L. WEILAND, OF ROCHESTER, NEW YORK.

DESIGN FOR A THERMOMETER-BACK.

SPECIFICATION forming part of Design No. 18,405, dated June 19, 1868.

Application filed February 8, 1868. Serial No. 203,427. Term of patent 3½ years.

To all whom it may concern:

Be it known that I, HENRY L. WEILAND, a citizen of the United States, residing at Rochester, in the county of Monroe and State of New York, have invented and produced a new and original Design for Thermometer-Backs, of which the following is a specification, reference being had to the accompanying drawings, forming part thereof.

- 10 Figure 1 is a perspective view of my newly-designed thermometer, and Fig. 2 a cross-sectional view of the same, these two views being deemed necessary to fully illustrate my design.
- 15 The leading feature of my design consists of a thermometer-back having two faces sloping

downwardly and outwardly from the longitudinal center and inclining backward at an angle to the vertical walls or edges of the horizontal base, one face of the thermometer plate being upon each side of the tube, as shown.

I claim—

The design for a thermometer herein shown and described, the same consisting of a thermometer-back with sloping sides, one thermometer-face being placed upon each side sloping from the tube.

HENRY L. WEILAND.
